(57) **CLAIM**

The ornamental design for a wireless charging station as shown and described.

DESCRIPTION

FIG. 1 is a front, right perspective view of a wireless charging station;

FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a partially enlarged view of FIG. 1.

The broken lines shown on the drawings depict portions of the wireless charging station that form no part of the claimed design. The dot-dash boundary line depicts enlarged portions of the claimed design.

1 Claim, 9 Drawing Sheets
